UNITED STATES PATENT OFFICE.

CLAUD J. CLEFTON, OF OWATONNA, MINNESOTA, ASSIGNOR, BY DIRECT AND MESNE ASSIGNMENTS, TO RUTH P. CLEFTON, OF ST. PAUL, MINNESOTA.

ACETYLENE BURNER.

Application filed March 5, 1921. Serial No. 449,972.

To all whom it may concern:

Be it known that I, CLAUD J. CLEFTON, a citizen of the United States, resident of Owatonna, county of Steele, State of Minnesota, have invented certain new and useful Improvements in Acetylene Burners, of which the following is a specification.

The object of my invention is to provide a burner adapted generally for gas and particularly for acetylene gas in the handling of which great difficulty is experienced through the flaring back or popping of the gas in the mixing chamber when the flow is cut off. Such flare-back and the consequent explosion usually frightens the person handling the burner and renders the sale of the article difficult and sometimes impossible.

The invention consists generally in various constructions and combinations, all as hereinafter described and particularly pointed out in the claims.

In the accompanying drawings forming part of this specification,

Figure 1 is a plan view of a torch embodying my invention,

Figure 2 is a longitudinal sectional view of the same;

Figure 3 is a view, partially in section, showing the burner in use on a flat iron,

Figure 4 is a perspective view of a gas distributing device provided near the tip of the burner.

In the drawing, 2 represents a shell or casing having a mixing chamber 3 with ports 4 leading thereto and a threaded orifice 5 to receive a tip 6 that is connected with a hose 7 leading from a source of gas supply. The casing 2 has a passage 8 leading from the mixing chamber and communicating with a chamber 9 provided in the tip 10 of the burner, said tip having a tapered end 11 enclosing an orifice 12 through which the heating flame is projected. The tip is connected with the casing by suitable means, such as the threads 13 by means of which the tip can be conveniently removed from the casing or mounted thereon.

Within the chamber 9 I arrange a sleeve-like member 14 having a beveled end 15 to fit the inclined surface of the walls of the tip and at its other end a cone surface 16 is provided, having ribs or wings 17 thereon which bear on the adjacent end wall of the casing 2 and space the sleeve from said wall so that the gas may flow freely between the

wings 17 and around the sleeve in the chamber 9 between it and the walls of the burner. The walls of the sleeve I provide with a series of narrow slots 18 extending partially around the sleeve and close together so that the gas entering the chamber of the burner is deflected by the walls thereof to these slots and passing through them, may then reach the orifice or exit of the burner. The gas is compelled to make what is substantially two right angle turns, one to pass from the chamber 9 through the slots 18 into the space enclosed by the sleeve and the other in flowing from the slots to the orifice 12. The air, of course, is mixed with the gas in the burner in the usual way and I have found that there is no flare back or popping of the burning gas when the supply is cut off, as sometimes happens in lighting the gas. The flow to the tip of the burner is instantaneous, and it may be readily ignited and placed in the flat iron or any other position where it is desired to use the burner.

In Figure 3 I have shown the burner mounted in a flat iron which comprises a base 19 having a top or cover 20, a standard 21 and a hand grip 22 mounted on the standard. The burner is fitted into a socket 23 at one end of the base and a spring-pressed pin 24 engages a rib 25 on the surface of the burner for holding it in the socket of the iron. When this pin is lifted against the tension of the spring, the burner may be readily withdrawn from the iron. The angle of the burner is such in its socket that the flame therefrom is projected against the bottom of the iron so that it will be quickly and thoroughly heated.

I claim as my invention:

1. The combination, with a gas burner having a tip provided with a chamber and a tapered end having an orifice leading from said chamber, of a sleeve fitting within said chamber and having one end seated against the tapered walls of said end opposite said orifice and its side walls spaced from the corresponding walls of the burner to form an annular passage between them, the other end of said sleeve being tapered and imperforate and having means for deflecting the gas outwardly to said annular passage, and the walls of said sleeve having openings therein through which the gas is compelled to flow from said annular passage to reach the exit of the burner.

2. The combination, with a gas burner having a chamber therein, of a sleeve fitting within said chamber and its side walls spaced from the corresponding walls of the burner ⁵ to form an annular passage between them, said sleeve having a cone-shaped imperforate end provided with means for deflecting the gas outwardly to said annular passage and the walls of said sleeve having openings ¹⁰ therein through which the gas is compelled to flow from said annular passage to reach the exit of the burner.

3. The combination, with a gas burner

having a chamber therein, of a sleeve fitting within said chamber and spaced from the ¹⁵ walls of said burner to form an annular passage between them, one end of said sleeve being imperforate and having webs thereon for deflecting the gas outwardly to said passage, the walls of said sleeve having narrow slots ²⁰ therein through which the gas is compelled to flow from said annular passage to reach the exit of said burner.

In witness whereof I have hereunto set my hand this 28th day of February, 1921.

CLAUD J. CLEFTON.
